UNITED STATES PATENT OFFICE.

ADOLPH R. RAMIG, ADAM G. SHAFFER, AND ALEXANDER J. KRUMPECK, OF CHICAGO,
ILLINOIS; SAID KRUMPECK ASSIGNOR TO SAID RAMIG AND SAID SHAFFER.

RADIATOR CAP FOR AUTOMOBILES.

Application filed May 7, 1921. Serial No. 467,673.

To all whom it may concern:

Be it known that we, ADOLPH R. RAMIG, ADAM G. SHAFFER, and ALEXANDER J. KRUMPECK, citizens of the United States, and residents of Chicago, in the county of Cook and State of Illinois, have invented certain new and useful Improvements in Radiator Caps for Automobiles, of which the following, reference being had to the drawing accompanying and forming a part hereof, is a specification.

This invention relates to a device adapted to be secured to or over the aperture through which water may be poured into the radiator of water cooled internal combustion engines.

Among the objects of the invention is to obtain a cover which is easily applied to the aperture of the radiator, which is readily arranged, when applied, so that it cannot be removed until means adapted to contact with a locking device are manipulated in a predetermined manner; to obtain a cover which is not easily gotten out of order, or manipulated by an unauthorized person, which is readily operated by means of a key, which is not liable to be broken, which is simple in construction, economically made and durable.

30 In the drawing referred to Fig. 1 is a top plan view of the radiator cap embodying the invention;

Fig. 2 is a vertical longitudinal section of said cap, and

35 Fig. 3 a vertical section of a screw threaded member of the cap, in a partially completed condition.

And Fig. 4 is an elevation of one end of a punch adapted to simultaneously complete the construction of the member illustrated in Fig. 3 and join it to the member co-acting therewith to form the completed device.

40 A reference character applied to designate a given part indicates said part throughout the several figures of the drawing wherever the same appears.

A represents a member which is provided with an inverted cup center, a , having the internal annular flange a' , and extending arms a'' , a''' , one of said arms being provided with recess a'''' , in which a lock may be inserted. B represents a rotatable member of a lock, and b a pin which is eccentrically mounted on the end of rotatable

member B. C, C, represent recesses in the cylindrical wall of member D, and d an annular groove near the upper end of member D. Member D is cylindrical in form, and of ductile material, as say cast brass, 60 and at one end thereof is made with the inclined inner face d' , and the bottom of groove d is substantially parallel with face d' of said upper end of member D, prior to the joining of said member with member A, said member D being, prior to said joining substantially as is illustrated in Fig. 3. X, Fig. 4, represents the end of a punch which is adapted, when forced into and substantially through member D to force 70 the inclined face d' of said ring into substantially the same cylindrical plane with the remainder of the inner face of said member D; said punch being inserted in the holder of a punch press, in the ordinary 75 way. Prior to the forcing the upper end of member D outward, thereby expanding the metal of said member at said upper end, said end is inserted in member A, so that when said upper end is expanded, the flange 80 a' is contained in the groove d , and cannot be removed therefrom; but may be easily turned around in said groove, by turning member around by arms a'' , a''' , or otherwise. The lower end of member D is provided with screw threads fitting to corresponding screw threads on the walls of the aperture in the radiator which the device is intended to cover, as threads E. G represents the upper end of the radiator aperture. 85

To join members A and D so that turning of member A will turn member D we provide the bolt F which is longitudinally movable in member A, so that one end thereof may be forced forward and into one of the recesses C, C, and to control said longitudinal movement of bolt F, we provide the loop f adjacent to one end thereof, in which loop the pin b travels, as rotatable 95 member B of a lock is turned. The pin b travelling in loop f moves said bolt F, longitudinally, and said member B cannot be turned until the end of the bolt registers with a recess C, and when said bolt is to 100 be moved longitudinally said registration is made, and upon said bolt F entering one of said recesses C the members A and D are joined, so that rotation of the member A rotates member D and screw threads E en- 105 110

- gage with the screw threads of end G of the wall of the radiator aperture, and further turning of said members A, D, turns the device on to or off from said end G.
- 5 When the bolt F is retracted and withdrawn from the recess C, after the device is mounted on the end G, it cannot be removed therefrom until the member B of the lock is rotated to move bolt F to enter 10 a recess C, again, while at the same time it can be turned freely, that is, part A thereof can be turned without turning the member D. The device is thereby locked on the end G.
- 15 To prevent the device from being turned by the jars incident to driving an automobile on a road or street, we provide the longitudinally movable pin H, and spring h in one of the arms a''. I represents a plug in 20 said arm to provide an abutment against which one end of spring h rests, the other end abutting against said plug H.
- The end of the spring adjacent to member D is rounded so as to yieldingly engage 25 with the recesses C, C, in said part D; said engagement not being sufficient to turn member D by the turning of member A, however.
- 30 We claim:
1. A two-part radiator cap, consisting of a member provided with an inverted cup-shaped part provided with an inner annular flange and a recess to receive a rotatably mounted locking member, and a pin 35 eccentrically mounted on said locking member, in combination with a ring-shaped part provided with an annular groove arranged to co-act with said flange to join said parts and permit rotation of one thereof relative 40 to the other, a rotatable lock member, and

a longitudinally movable lock member provided with a loop at one end thereof arranged and connected to said rotatable lock member, to co-act with said eccentrically mounted pin to control the longitudinal movement of said locking member by the rotation of the locking member on which said pin is mounted, said ring-shaped part provided with a recess arranged to register with and receive said longitudinally movable bolt.

2. A radiator cap consisting of a member provided with an inverted cup-shaped member and arms extending radially on opposite sides thereof, said cup-shaped member provided with an inner annular flange, and with a recess adjacent to said cup-shaped member adapted to receive a rotatably mounted lock cylinder having a pin eccentrically mounted thereon, in combination with an additional member provided with an annular groove arranged to co-act with said annular flange to join said members and permit rotation of one thereof relative to the other, and said additional member provided with a radially extending recess, and a bolt mounted on said first member and connected to said eccentrically mounted pin to be moved longitudinally thereby into engagement with said radially extending recess to join said members and prevent rotation of one thereof relative to the other.
